LONDON, ENGLAND

REVERBERATORY FURNACE

Application filed August 7, 1931, Serial No. 555,798, and in Great Britain August 11, 1930.

This invention relates to improvements in reverberatory furnaces and whilst it is of particular value for use in melting relatively small charges of ferrous as well as non-ferrous metals and alloys, it is not restricted thereto. The primary objects of the present invention are to economize fuel and to reduce to a minimum the loss of metal due to burning or oxidation during the process of melting.

10 According to the present invention, a reverberatory furnace comprises a metal casing, the bottom of which is of an arc-shaped form in transverse section, an inner lining of refractory material to form a hollowed bed of a semi-cylindrical shape in cross section, an uptake through which the products of combustion escape, means for continuously oscillating or rocking the furnace to and fro during melting, a stationary burner arranged 15 at the axis of oscillation of the furnace and projecting through an orifice in the end wall of the furnace opposite the uptake end, the said burner being so positioned that the flames or gases of combustion are directed 20 downwardly to impinge on the surface of the metal in the bed and on to the surface of the bed exposed by the movement of the metal therein due to the oscillation of the furnace, a hood, in communication with a 25 chimney, arranged above the uptake and so shaped as to receive the products of combustion escaping from said uptake irrespective of any angular position of the furnace, a charging door in said hood so arranged as to 30 charge the metal into the uptake for pre-heating it therein, tapping and slagging spouts in the furnace, and means for supplying air under pressure to the burner and pre-heating said air by causing it to pass through 35 pipes heated by the escaping gases of combustion.

This invention will be now more particularly described making reference to the accompanying drawing in which:—

45 Fig. 1 is a view in side elevation—partly in section on line I—I of Fig. 2—of a reverberatory furnace embodying this invention, and

50 Fig. 2 is a view in end elevation partly in section on line II—II of Fig. 1.

Throughout both views similar parts are marked with like letters of reference.

According to the present invention, a furnace comprises a metal casing *a*, the bottom of which is of an arc-shaped form, an inner lining of refractory material to form a hollowed bed *b* of a semi-circular shape in cross section, a combustion chamber *c* above said bed, a tapping spout *d*, a slagging spout *e*, means for continuously rocking the furnace about a longitudinal axis *y* so as to rock the metal *x*—within limits—within the bed *b*, and means for heating the furnace such as an oil, gas or pulverized fuel burner or oil atomizer *f*. The burner *f*, which is stationary, is located at the axis *y* of oscillation of the furnace and projects through an orifice *f*¹ in the end wall of the furnace. The burner *f* is also so positioned that the flames or products of combustion are directed downwardly to impinge on the surface of the metal *x* and the surface of the bed *b* exposed by the movement of the metal within the bed due to the oscillation of the furnace.

Any suitable means may be provided for 75 rocking the furnace for instance it may be mounted on trunnions or preferably the arc-shaped bottom of the casing *a* is supported by wheels or rollers *g* and provided with a pair of racks *h* adapted to be engaged by toothed 80 pinions *i* carried by a shaft *i*¹ mounted in suitable bearings. The shaft *i*¹ is driven alternately in opposite directions by any suitable form of gearing. The rocking movement of the furnace is limited in each direction. 85 The products of combustion escape through the uptake *k* situate at the opposite end to the burner *f*. The lower part of a chimney shaft *l*^{*} is flared or arc-shaped to form a hood *l* above the uptake *k*, which is provided 90 with inwardly and downwardly sloping members *l*¹, the arrangement being such that the products of combustion escaping from the uptake *k* are received by the chimney shaft *l*^{*} irrespective of any angular position the furnace can assume. The chimney shaft *l*^{*} is formed with a soot chamber *l*² which is normally closed by a door *l*⁴. The metal is charged into the uptake *k* through an opening in the hood *l* normally closed by a door 100

l^1 hinged at l^2 to the hood l , as shown so that the combustion gases escaping through the uptake l^3 pre-heat the metal before it passes to the hollowed bed b .

5 In the construction illustrated, powdered fuel with air under pressure is supplied to the burner f . The air may be heated by passing it through a tube recuperator l^2 carried in a passage l^6 forming the outlet for 10 the chimney shaft l^4 above the hood l and immediately above the soot chamber l^5 .

It is found in practice that with a furnace embodying this invention, not only is the metal reduced to a molten state in less time 15 than usual, with a consequent saving of fuel, but the quality of the metal—particularly in the case of alloys—is improved.

We declare that what we claim and desire to secure by Letters Patent is:—

20 A reverberatory furnace comprising a metal casing, the bottom of which is of an arc-shaped form in transverse section, an inner lining of refractory material to form a hollowed bed of a semi-cylindrical shape in 25 cross section, a combustion chamber above said bed, an uptake extending upwardly from the combustion chamber, through which the products of combustion escape, means for continually oscillating or rocking the furnace to and fro during melting, a stationary burner arranged at the axis of oscillation of the furnace and projecting through an orifice in the end wall of the furnace opposite to the uptake end, the said burner being so 30 positioned that the flames or gases of combustion are directed downwardly to impinge on the surface of the metal in the bed and on the surface of the bed exposed by the movement of the metal therein due to the oscillation of 35 the furnace, a hood of a flared or arc-shaped form terminating the lower end of a chimney shaft and arranged above the uptake, inwardly and downwardly sloping members carried by the uptake and co-acting with the arc-shaped hood to receive the products of combustion escaping from said uptake irrespectively of any angular position of the furnace, a 40 door closing a charging opening formed in one side of the hood, said opening being so arranged as to charge the metal into the shaft whereby the combustion gases escaping through said uptake heat the metal before the latter passes to the hollowed bed, tapping and slagging spouts in the furnace, means 45 for supplying air under pressure to the burner and means for pre-heating said air by causing it to pass through pipes heated by the escaping products of combustion, as set forth.
